APPARATUS FOR MANUFACTURING ELECTRON DISCHARGE DEVICES

William S. Brian, Owensboro, Ky., assignor, by
mesne assignments, to General Electric Company,
a corporation of New York

Application November 23, 1944, Serial No. 564,768

5 Claims. (Cl. 316—19)

1

This invention relates to a method of and apparatus for manufacturing electron discharge devices such as vacuum tubes and more particularly to such a method and apparatus by means of which the exhaust, baking-out and degassing of a vacuum tube are conducted within an exhaustible container in the nature of a bell jar and the use of an exhausting and sealing tubulation is avoided. While the invention is of general application in the manufacture of electron discharge devices, it is particularly suitable for use in the manufacture of devices of the type disclosed and claimed in my copending application Serial No. 557,126, filed October 4, 1944, and entitled "Electron discharge device and electrode assembly therefor."

In the manufacture of conventional tubes, it is customary to mount the various tube electrodes on a supporting sealing stem or press through which the lead-in conductors pass. This assembly is then enclosed within and sealed to an envelope provided with an exhausting and sealing tubulation and usually having a configuration cooperating with mica spacing washers to locate the electrode structure accurately and rigidly within the envelope. The exhausting tubulation is generally connected to an exhausting manifold and while so connected the device is passed through a baking-out oven for degassing, whereupon the tubulation is sealed off and severed from the exhaust manifold. Usually the process just described is conducted continuously by means of automatic machinery.

The process described has a number of limitations which it is desirable to avoid. For example, the exhaust is effected through a restricted tubulation which considerably limits the rate of exhaust, resulting either in an extended exhaust period or a lower degree of vacuum than is desired. Furthermore, the exhaust tubulation, which is tipped off or sealed after the exhaust operation, constitutes a weak point in the physical structure of the tube and must be protected from breakage in some way, either by a mounting base or some form of guard.

It has also been proposed heretofore to exhaust and bake out vacuum tubes within an exhausted container, such as a bell jar, but the types of devices to which such a process has heretofore been applied have been such that the process has proved impracticable.

It is a general object of the invention, therefore, to provide a new and improved method of and apparatus for manufacturing electron discharge devices which avoid one or more of the above-named disadvantages and limitations of the systems of the prior art.

It is another object of the invention to provide a new and improved method of and apparatus for manufacturing electron discharge devices in which the assembly of the electrodes and

other tube elements is effected substantially completely automatically, thereby involving a minimum number of manual operations.

It is another object of the invention to provide a new and improved method of and apparatus for manufacturing electron discharge devices in which the exhaust, baking-out and degassing are conducted within an exhaustible container and without the use of an exhausting and sealing tubulation.

In accordance with the invention, the method of manufacturing an electron discharge device including a unitary electrode assembly comprises supporting an electrode assembly from a sealing stem having an annular sealing surface, subjecting the electrode assembly and stem simultaneously to exhausting and heating media to degas the same, and sealing at least one enclosing shell to the stem while the assembly is subjected to the exhausting and heating media.

Further in accordance with the invention, apparatus for manufacturing electron discharge devices of the type including a unitary electrode assembly, a sealing stem and at least one enclosing shell comprises an exhaustible container including a removable cover portion, means within the container for supporting the electrode assembly and stem, and means within the container for supporting the shell in spaced relation to the sealing stem. The apparatus also includes means for subjecting the assembly, stem and shell to an exhausting and heating media and means external to the container for initiating relative movement between the two supporting means to bring the shell into sealing engagement with the stem while subject to the exhausting and heating media.

For a better understanding of the invention, together with other and further objects thereof, reference is had to the following description taken in connection with the accompanying drawings while its scope will be pointed out in the appended claims.

In the drawings, Figs. 1a, 1b and 1c represent a cathode in successive stages of assembly; Fig. 2a is an elevational view illustrating schematically apparatus for manufacturing grid electrodes, Fig. 2b is a plan view showing the material from which the grid electrodes are manufactured as it appears after each operation, and Fig. 2c shows an elevational and plan view of the completed grid electrode; Fig. 3a illustrates schematically the successive steps of assembling the unitary electrode assembly and Fig. 3b is an elevational view of a machine for dispensing the elements in succession in accordance with the steps illustrated in Fig. 3a; Fig. 4 is a perspective view of a unitary electrode assembly mounted in its supporting sealing stem; while Fig. 5a is an elevational view, partly in section, of an apparatus for practicing the method of the invention in exhausting, bak-

ing-out and degassing the electron discharge device, Fig. 5b is a cross-sectional detail showing the positional relation of the components of the electron discharge device in the apparatus of Fig. 5a during treatment, and Fig. 5c is a perspective view of one of the supports shown in Fig. 5a.

Referring now to Figs. 1a, 1b and 1c, there is illustrated the method of assembling the cathode element of an electron discharge device to be manufactured in accordance with the invention. In these figures, a pair of opposed annular cup-like elements 10a and 10b are assembled with a triangular frame or yoke 11 therebetween which is bonded to both of the elements 10a and 10b, as by welding, and serves to secure the elements together as indicated in Fig. 1b. A toroidal indirectly heated cathode 12 having extending lugs or ears 12a is secured in position by welding or otherwise bonding the tabs 12a to the yoke 11. Suitable cathode heater lead-in conductors 12b are brought out through a gap 10c in the elements 10a, 10b which if desired may connect with a tubular protecting extension 10d. While the details of the cathode structure may vary in accordance with the design requirements of a particular tube, the resulting cathode is preferably in accordance with the design illustrated in my above-mentioned copending application.

In Figs. 2a and 2b there is illustrated the method, in accordance with the invention, of manufacturing grid electrodes for embodiment in the electron discharge device constructed in accordance with the method of the invention. The method represented in Figs. 2a and 2b comprises intermittently feeding a continuous metallic sheet or ribbon 15 to a plurality of successive operating stations A, B, C and D. The metal ribbon 15 may be supplied from a suitable feed roll or spool 16 and is passed over one or more guide rolls 17, past the stations A-D, inclusive, and to an indexing mechanism 18 which imparts to the ribbon 15 an intermittent step-by-step advance. At station A there is provided a punch or die for punching in the ribbon 15 spaced apertures 15a, preferably of circular configuration. Between the stations A and B there is fed a superimposed continuous ribbon 19 of metallic grid, this ribbon being fed intermittently and synchronously with the ribbon 15. The term grid is used in its generic sense to include a group of parallel wires, a mesh or screen or a perforated sheet. The ribbon 19 may be supplied from a feed roller or spool 20 and passed over one or more guide rollers or spools 21 and through the indexing mechanism 18. Station B comprises a punch or die for deforming the grid 19 within each aperture into a dish-like configuration 19a having a plane bottom parallel to the plane of the ribbons 15 and 19. Station C includes provisions for line welding or otherwise bonding the grid ribbon 19 to the apertured ribbon 15 about the periphery of each aperture; that is, station C may comprise a suitable electric resistance welder. At station D there is provided a die or punch for punching from the superimposed ribbons 15 and 19 a series of composite disks, each of a diameter larger than the apertures in the ribbon 15, the resulting apertures in the superimposed ribbons being represented at 15b. A detail of resulting composite disk is shown in Fig. 2c, in both plan and cross section, from which it is seen that the dish-like grid portions 19a are surrounded by an annular frame or flange 19b to which the peripheral portion of the grid or mesh 19a is welded, thus providing an accurately formed, rigid grid electrode.

In order to ensure synchronism between the several operations performed at stations A, B, C and D, there is provided a common driving mechanism 22 which, by means of a shaft 23, actuates the forming mechanism at each of the stations, as represented schematically by the several crank and link mechanisms 23a, 23b, 23c and 23d, and which also actuates the indexing mechanism 18 to advance the superimposed ribbons 15 and 19 an appropriate distance between each successive operation. It will be understood that the details of the mechanism for practicing the method described form no part of the present invention but that such a mechanism may be of any conventional type. The method of forming electrodes described above is claimed in my divisional application, Serial No. 610,794, filed August 14, 1945.

Referring now to Figs. 3a and 3b, there is represented schematically apparatus by means of which there may be practiced the method of assembling the several electrodes of the electron discharge device being manufactured in their desired relationship within a retaining shell of insulation material to form a unitary electrode assembly. Referring particularly to Fig. 3b there is represented a circular stationary head 25 including a plurality of loading magazines 25a for carrying groups of individual electrode elements or parts and provided with suitable dispensers for dispensing such elements singly. The stationary head 25 is supported on a base or table 26 but spaced therefrom. Between the head 25 and the table 26 is disposed a rotatable table or drum 27 carrying a plurality of loading heads 27a. The rotatable table 27 is provided with indexing mechanism, not shown, so that each of the loading heads 27a stops successively under each of the magazines 25a to receive the several electrode elements or parts in their proper sequence. The loading heads 27a, after each indexing movement, are raised by a suitable cam mechanism, not shown, under one of the magazines 25a to trip the dispensing mechanism associated therewith and receive a part. The magazine 25b represents schematically the unloading receptacle or magazine from which the complete electrode assembly is removed.

The several electrode elements and parts going to make up a unitary electrode assembly of the type disclosed and claimed in my above-mentioned copending application are represented in Fig. 3a opposite their respective positions in the stationary head 25 from which they are dispensed. In the specific assembly represented, the elements are, in their order of assembly, an anode 28; a ceramic retainer shell 29; a ceramic spacer ring 30; a grid electrode 31 of the type resulting from the method described above in connection with Figs. 2a, 2b and 2c, and in this case functioning as a suppressor grid; a second ceramic spacer ring 30; a second grid 32 which may be of a different design and proportioning than the grid 31 and in this case functioning as a screen grid; a ceramic spacer ring 30; a third grid 33 which in this case is a control grid; a ceramic spacer ring 30; a cathode assembly 34, which may be of the type resulting from the method described in connection with Figs. 1a, 1b and 1c; a second ceramic retainer shell 29; a ceramic spacer ring 30; a fourth grid 35, in this instance a control grid; a ceramic spacer ring 30; a fifth grid 36, in this instance a screen grid; a ceramic spacer ring 30; a sixth grid 37, in this case a suppressor grid; a ceramic ring 30; and a second anode 28, the complete electrode assembly being as represented by

the unit 38 opposite the unloading position of the magazine head 25.

The unitary electrode assembly fabricated as just described is thereupon supported from a sealing stem having an annular sealing surface and preferably, as shown in Fig. 4, comprising an annular ring 39 surrounding the electrode assembly 38 and provided with opposed upper and lower annular sealing surfaces. The ring 39 is preferably of lead glass and has a temperature-coefficient - of - expansion substantially matching that of the tube envelope described hereinafter. This ring 39 is provided with a plurality of radial slots 39a shown in dotted lines, these slots extending approximately half-way through the thickness of the ring. Mounted within these slots are a plurality of lead-in conductors 39b for making connection to the electrodes comprised within the assembly 38, two of the lead-in conductors 39b being soldered or otherwise bonded to eyelets 28a formed on the anodes 28 and constituting the sole support of the electrode assembly 38 within the annular sealing stem 39. Others of the lead-in conductors 39b may be connected to the other electrodes of the assembly in a conventional manner, certain of these connections being illustrated. After the parts are positioned as illustrated, the annular ring 39 is subjected to heat and pressure in a forming die which fuses the glass ring 39 sufficiently to close the slots 39a and seal the ring 39 about the lead-in conductors 39b, thus providing a unitary rigid structure composed of the electrode assembly 38 and its surrounding annular sealing stem 39.

The apparatus for completing the manufacture of electron discharge devices of the type described, including a unitary electrode assembly, a surrounding sealing stem, and at least one enclosing shell, preferably two opposed enclosing shells, is represented in Fig. 5a. This apparatus comprises an exhaustible container 40, preferably of non-conductive material such as the glass commercially available as Corning type 705. The container 40 is sealed to a metal mounting ring 41, preferably of a cobalt, nickel and iron alloy commercially available under the trade name "Kovar," having a temperature-coefficient-of-expansion substantially matching that of the glass container 40. The ring 41 is provided with an internal supporting disk 42 having a plurality of enlarged apertures 42a opening into the bottom of the ring 41 which is adapted for connection to a suitable exhaust pump or manifold through valves, not shown. The container 40 is provided with an outwardly extending peripheral flange 40a in which is seated a removable cover portion 40b, preferably also of glass, which is adapted to sit in the annular flange 40a on a seal or cushion 43 of rubber or equivalent sealing material. It is found that normally the atmospheric pressure acting on the cover portion 40b is sufficient to maintain an air-tight seal at the flange 40a.

There are provided means for supporting within the exhaustible container 40 the electrode assembly and steam structure, as well as means for supporting two enclosing shells for the electrode assembly in spaced relation to the stem and on opposite sides thereof. The desired space relationship of the components is represented in Fig. 5b in which the electrode assembly 38 and annular sealing stem 39 are shown with upper and lower substantially hemispherical enclosing shells 44 and 45 spaced from the opposing sealing surfaces of the sealing stem 39. Specifically,

the supporting means for the electrode assembly 38, the stem 39 and shells 44 and 45 comprises a central supporting post 46 mounted from the disk 42 and extending vertically within the chamber 40. A stationary ceramic ring or jig 47 is supported from an auxiliary ceramic platform 48, rigidly secured to the post 46, by means of posts or struts 49 provided with threaded portions 49a cooperating with nuts 50 for accurately positioning vertically the jig 47 which, in turn, positions and supports the electrode assembly 38 and sealing stem 39. There is also provided a ceramic supporting ring or jig 51 for the upper shell 44, the jig 51 being supported by posts or struts 52 from a ceramic platform 53 in turn supported on a sleeve 54 slidably mounted on the post 46. The jig 51 merely rests on its supports so that it can be lifted off when the tube is completed. There is also provided a third ceramic jig or ring 55 for supporting the lower sealing shell 45, the jig 55 being supported from a sleeve 56 sliding on post 46 and on which, in turn, the sleeve 54 of jig 51 slides.

The apparatus of Fig. 5a also includes means for biasing the jigs 51 and 55 to bring the shells 44 and 45 into sealing engagement with the stem 39. The biasing means of the upper jig 51 comprises merely the weight of the jig and its associated elements which tend to drop, bringing the lower rim of the shell 44 into sealing engagement with the upper face of the stem 38. The biasing means for the jig 55 comprises a coil spring 57 acting on a flange 56a of sleeve 56, biasing the jig 55 to move the lower enclosing shell 45 upwardly until its upper rim engages the lower sealing surface of the stem 39.

The apparatus of Fig. 5a also includes latching means for normally restraining the supporting means of the several vacuum tube elements from stem engaging movement. Specifically, latching means comprises a pin 58 supported by pivoted link mechanism 59 for horizontal movement to engage overlapping slots in the sleeves 54 and 56, to hold the jigs 51 and 55 in such relative positions that the shells 44 and 45 are spaced from the stem 39 as shown in Fig. 5b. The pin is mounted in a side arm 40c of container 40 and is biased into engagement with the slots in sleeves 54 and 56 by means such as a biasing spring 58a. As described herein-after, this relationship is maintained during the exhausting and baking-out process. To this end, there are provided means for subjecting the electrode assembly 38, the stem 39 and the shells 44 and 45 to exhausting and heating media. These elements are subjected to an exhausting media or vacuum by evacuating the container 40 by means of a suitable exhaust pump, in the conventional manner. The means for subjecting these elements to a heating medium comprises a coil 60 surrounding the container 40 in the vicinity of the elements 38, 39, 44 and 45 and adapted to be connected to a high-frequency source 61 through a switch 62 for producing within the container 40 a high-frequency electromagnetic field to heat the electrode assembly 38 and the shells 44 and 45 to baking-out temperature inductively. The winding 60 is preferably constructed of hollow tubing and coupled to a source of cooling fluid such as water, as indicated.

The apparatus of Fig. 5a also includes means external to the container 40 for initiating relative movement between the supporting means for the electrode assembly 38 and stem 39 and the

supporting means for one or both of the shells 44, 45 to bring the shells into sealing engagement with the stem while the container 40 is exhausted and the elements are being heated by the high-frequency field of the coil 60. This means comprises a solenoid 63 surrounding the side arm 40c and acting on the pin 58 as an armature and adapted to be connected to a suitable source, such as a battery 64, through a switch 65. Upon closure of the switch 65, the solenoid 63 is energized to retract the pin 58 against the bias of the spring 58a and release the sleeves 54 and 56 to permit movement of the jigs 51 and 55 to bring the shells 44 and 45 into sealing engagement with the stem 39.

It is believed that the method of manufacturing an electron discharge device including a unitary electrode assembly effected by the apparatus of Fig. 5a will be clear in view of the foregoing description. Briefly, the movable cover portion 40b of the container is removed and an electrode assembly 38, supported from a sealing stem 39 having a pair of opposed annular sealing surfaces, as by means of the lead-in conductors 39b extending through the substantially annular stem 39, is disposed in the exhaustible container 40, supported in the jig 41. The shells 44 and 45 are thereupon disposed within the container 40, supported in their respective positions in the jigs 51 and 55, respectively, and in spaced relation to the opposite sides of stem 39. The removable cover portion 40b of the exhaustible container 40 is then replaced. The container 40 is thereupon exhausted and the electrode assembly 38 and shells 44, 45 are simultaneously heated by means of the high-frequency electromagnetic field developed by the coil 60 upon excitation from the high-frequency source 61. The action of the high-frequency electromagnetic field is effective to raise the temperature of the shells 44 and 45 and of the various metal elements of the electrode assembly 38 to very high temperatures, this heat being transmitted to the non-conductive elements of the assembly. This heating is continued to the point where all of the occluded gases are driven off, the container 40 being continuously exhausted during this heating or baking period.

When this process is completed, the solenoid 63 is energized through switch 65 to release the jigs 51 and 55 which, under the influence of their biases, move the shells 44 and 45 into sealing engagement with opposite faces of the sealing stem 39, the heating and exhausting process being continued. The shells 44 and 45 become heated to such a degree that they fuse the portions of the glass stem 39 with which they come in contact. Due to the fact that glass has an extremely high negative temperature-coefficient-of-resistance, the portions of the fused glass become appreciably conductive and absorb additional heat from the high-frequency electromagnetic field, thereby aiding in the sealing process. When this sealing process is complete, the excitation of the winding 60 is interrupted and the parts are allowed to cool sufficiently to cause "freezing" of the seals between the stem 39 and the shells 44 and 45. The connection from the exhaustible container 40 to the exhaust pump is then broken, atmospheric pressure is admitted, the cover portion 40b removed, and the jigs 51 and 55 restored to their normal spaced positions in which they are held by the latch pin 58. The completed electron discharge device may then be removed from jig 41 and the apparatus is ready

for the processing of a second electron discharge device.

In practice, the apparatus of Fig. 5 will be duplicated in a bank of containers preferably moving around a closed path so that the manufacture of the discharge device can be made continuous and substantially automatic.

While the method and apparatus of the invention have been described in connection with the manufacture of an electron discharge device comprising a unitary electrode assembly supported from a sealing stem and provided with a pair of opposed enclosing shells, it is apparent that it is also applicable to the manufacture of such a device in which the sealing stem is a circular disk and only a single enclosing shell is provided.

While there has been described what is at present considered to be the preferred embodiment of the invention, it will be apparent to those skilled in the art that various changes and modification may be made therein without departing from the spirit or scope of the invention.

What is claimed as new is:

23. Apparatus for manufacturing electron discharge devices of the type including a unitary electrode assembly, a sealing stem and at least one enclosing shell comprising, an exhaustible container, means within said container for supporting said electrode assembly and stem in fixed relation, means within said container for supporting said shell in spaced relation to said stem, means for subjecting said assembly, said stem and said shell to exhausting and heating media, and means external to said container for initiating movement of said second supporting means to bring said shell into sealing engagement with said stem while subject to said exhausting and heating media.

40. Apparatus for manufacturing electron discharge devices of the type including a unitary electrode assembly, a sealing stem and at least one enclosing shell comprising, an exhaustible container including a removable cover portion, means within said container for supporting said electrode assembly and stem in fixed relation to said container, means within said container for supporting said shell in spaced relation to said stem, means for subjecting said assembly, said stem and said shell to exhausting and heating media, and means external to said container for initiating movement of said second supporting means to bring said shell into sealing engagement with said stem while subject to said exhausting and heating media.

60. Apparatus for manufacturing electron discharge devices of the type including a unitary electrode assembly, a sealing stem and a pair of enclosing shells comprising, an exhaustible container, a first jig within said container for positioning and supporting said electrode assembly and stem in fixed relation to said container, second and third jigs within said container and on opposite sides of said first jig for positioning and supporting said shells in spaced relation to said stem, means for subjecting said assembly, said stem and said shell to exhausting and heating media, and means external to said container for initiating movement of said second and third supporting jigs to bring said shells into sealing engagement with said stem while subject to said exhausting and heating media.

70. Apparatus for manufacturing electron discharge devices of the type including a unitary electrode assembly, a sealing stem and at least

one enclosing shell comprising, an exhaustible container, means within said container for supporting said electrode assembly and stem, means within said container for supporting said shell in spaced relation to said stem, means for subjecting said assembly, said stem and said shell to exhausting and heating media, means for biasing said two supporting means to bring said shell into sealing engagement with said stem, latching means for normally restraining said supporting means from stem-engaging movement, and means external to said container for releasing said latching means.

5. Apparatus for manufacturing electron discharge devices of the type including a unitary electrode assembly, an annular sealing stem surrounding said assembly and a pair of opposed enclosing shells comprising, an exhaustible container, a central supporting post in said container, a first jig mounted on said post for positioning and supporting said electrode assembly and stem, second and third jigs slidably mounted on said post for supporting said shells, means for biasing said second and third jigs to bring said shells into sealing engagement with said stem, latching means for normally holding said second and third jigs in such relative positions

that said shells are spaced from said stem, means for subjecting said assembly, said stem and said shells to exhausting and heating media, and means external to said container for releasing said latching means.
